INVENTOR:

WILLIAM R. CLARK,

By: Otto D. Runges,
his Atty.

UNITED STATES PATENT OFFICE.

WILLIAM R. CLARK, OF SAN DIEGO, CALIFORNIA.

SECURITY DEVICE FOR CLOTHING.

Application filed January 13, 1925, Serial No. 2,127. Renewed January 30, 1926.

To all whom it may concern:

Be it known that I, WILLIAM R. CLARK, a citizen of the United States, residing at San Diego, in the county of San Diego and State of California, have invented a new and useful Security Device for Clothing, of which the following is a specification.

This invention relates to devices to be attached to clothing and wearing apparel for securely holding articles of value, as pocket-books, purses, jewelry, and the like.

One of the objects of this invention is to provide a device by which a pocket-opening can be kept clamped so as to hinder a removing of articles from the pocket.

Another object is to provide a device that can be disposed within the opening of a pocket so as to obstruct the passage into the pocket.

Another object is to provide a device by which the opening of a pocket can be controlled so that the device must be operated first before any article can be passed through the opening.

Other objects will appear from the following description and appended claims as well as from the accompanying drawing, in which—

Fig. 1 is a portion of clothing having the trimming of a pocket-opening outlined thereon in full lines, and having a security device indicated in dotted lines to illustrate the proper position for such a security device within the pocket.

Fig. 2 is a front elevation of a simple form of a security device, embodying the invention.

Fig. 3 is a top-edge view of the device in Fig. 2.

Fig. 4 is a top-edge view of the device illustrated in Fig. 2 in opened position when pressure is applied to the ends of the device so that articles may be passed through the same.

Fig. 5 is a fragmentary rear-side elevation, illustrating the interconnection of the main spring-members and inserted link-members, as seen in the direction of the arrow 5 in Fig. 3.

Fig. 6 is a fragmentary sectional view on lines 6—6 of Fig. 5, illustrating the action of the coil spring between one of the main spring-members and the link.

Fig. 7 is a fragmentary front elevation

of one of the main spring-members provided with eyelets, by which the spring-members can be secured to the clothing.

Fig. 8 is a general cross section through a main spring-member, having shimmy or other similar suitable material applied to the same, by which such a member can be secured to clothing.

Fig. 9 is a top-edge view of a slightly modified form of two directly interconnected main-spring-members.

Carrying valuables loosely in a pocket makes them liable to loss by falling out of the pocket when a person stoops over to such an extent that the opening of the pocket reaches a position below the main portion of the pocket, and by making such valuables easily accessible to the fingers of a pick-pocket.

This invention is intended for the purpose of keeping the material of a pocket so closed that an article may be carried in a pocket safely.

The vest-pocket of men-clothing is normally provided with trimmings of the shape as indicated at 9 in Fig. 1, of slanting form, but, of course, a security-device can also easily be formed to fit into squarely shaped pocket-openings. The outlines of such a security-device are indicated in dotted lines at 10 behind such a trimming 9, to be within the opening of a pocket.

One practical form of such a security-device is illustrated in Figs. 2, 3, 4, 5 and 6. In this form, the one main spring-member 11 is of slightly longer shape than the second main spring-member 12.

Of course, the two main spring members may be of equal length, as represented by the members 23 and 24 in the slightly modified form in Fig. 9, and I do not limit myself to such and other minor details, the principal object being to provide some means by which the two opposite edges of the opening in a pocket may be securely kept in suitable relation to each other.

The form illustrated in Figs. 2, 3, 4, 5 and 6 offers the advantage that a pocket-opening may be opened rather squarely in the corners of the pocket-opening, as brought out in the illustration of Fig. 4. A further point is that the spring-member 12 may be left unaffected, or in a practically straight condition, which is desirable since the mem-

ber 12 is closest to the body of a person, and, in this manner, does not unduly press against the body of the person.

This form is for this reason provided with 5 link-members 13, pivotally or swingably engaging with the ends of the two main spring-members 11 and 12. To force the shorter spring-member 12 against the larger or front spring-member 11, a coil-spring 14 10 is inserted between each link-member 13 and the member 12, as more clearly illustrated in the rear-view of this interconnection in Fig. 5. One end 15 is disposed to engage with the member 12, and the other 15 end 16 of the spring 14 is disposed to engage with the link 13. The tension of the spring 14 has the tendency to force the member 12 towards the member 11, by imparting a 20 turning or swinging force to the link-member 13, as will easily be understood without further illustration or description. This turning and swinging force of the link-member may also be understood and realized from the illustration in Fig. 6.

25 The whole device, if made of a suitable size, may be forced into the opening of a pocket, to retain its proper position within such pocket-opening, however, it is preferably secured to the material surrounding such a pocket, as by sewing, or in any other similar suitable manner.

In Fig. 7, a portion 17 of a spring-member is illustrated with eyelets 18, by which such a spring-member may be sewed to or 30 united with the material of a pocket.

Of course, no special eyelets are required, a perforation of the spring-members by small holes may serve for the purpose of 35 suitably securing the device.

40 Another slightly modified form of securing means is illustrated in Fig. 8. The spring member 19, being illustrated in a general cross section, is covered on the two flat sides with suitable material 20 and 21, 45 secured along the longitudinal edges as indicated at 22. The material at 20 and 21 may be of so-called shimmy, or thin leather, or cloth, or any other similar suitable material, by which the spring-members can be

covered, and by which the covered spring-members can be secured to the pocket.

While the main spring-members are illustrated in Figs. 2, 3, 4, 5, 7 and 8, as made of sheet material, it must be understood that a device can just as well be made of wire material. Especially, the plain form illustrated in Fig. 9 can easily be made of wire material, looped or formed at the ends 55 to suitably interengage. Such devices, made of wire material, will be fully sufficient and strong enough to properly serve for the purpose for which they are intended.

Having thus described my invention, I claim:

1. In a safety device of the class described, a main spring member of a length to fit into the opening of a pocket, a second spring member of slightly shorter length, link-members engaged between the ends of 70 the two spring members, and other spring members disposed between the first- and second-named spring-members in operative connection with the link-members to form a yielding tension between the said members 75 whereby the first- and second-named members are normally pressed towards each other.

2. In a safety device of the class described, a main spring-member of a length to fit into the opening of a pocket, a second spring-member of slightly shorter length, both spring-members having engaging means at their ends for interengaging purposes and having other means to allow a 80 securing to the material of a pocket so as to allow a holding and controlling of the pocket by the spring-members, link-members inserted between the said spring-members, and other spring-members engaged 85 with the link-members and inserted between the link-members and the main spring members to force the spring members towards each other.

90 In testimony that I claim the foregoing 95 as my invention I have signed my name.

WILLIAM R. CLARK.
